UNITED STATES PATENT OFFICE

169,709

HANDKERCHIEF OR THE LIKE

Margaret Sauer, Shaker Heights, Ohio, and Herman Schmidt, New York, N. Y.

Application December 3, 1952, Serial No. 22,532

Term of patent 7 years

(Cl. D3—12)

To all whom it may concern:

Be it known that we, Margaret Sauer and Herman Schmidt, both citizens of the United States and residents of 3329 Sutton Road, Shaker Heights, Ohio, and 389—5th Avenue, New York, New York, respectively, have invented a new, original, and ornamental Design for a Handkerchief or the like, of which the following is a specification, reference being had to the accompanying drawings, forming part thereof.

The figure is a plan view of a handkerchief or the like, showing our new design.

We claim:

The ornamental design for a handkerchief or the like, substantially as shown.

MARGARET SAUER.
HERMAN SCHMIDT.
